HOLDING AND CENTERING DEVICE FOR
SPINNING, TWISTING, AND LIKE MA-
CHINES

Luigi Marzoli, Palazzolo sull'Oglio, Italy

Application February 3, 1940, Serial No. 317,089
In Italy February 24, 1939

5 Claims. (Cl. 57—129)

This invention relates to a device for holding and centering a body placed on a swiftly rotating spindle by means of independent members acting in a radial direction, more particularly adapted for spinning, twisting and like machines. This device is characterized in that said members act chiefly by effect of their own weight and are subjected to the action of a single central spring having chiefly the purpose of holding said members against the body to be centered placed on the spindle.

According to this invention said members are constituted by balls seated in openings, the axis of which is inclined towards the spindle end. The balls are introduced through said holes and are prevented from projecting from the spindle surface beyond a maximum extent set by a ring or cap secured in a suitable seating of the spindle. A single spring operates the balls through a cone or ball.

The device according to this invention has the advantage that the centrifugal force acting on the balls serves to hold the bodies placed on the spindle resiliently centered to an extent, which is the greater the higher the speed of rotation of the spindle is.

The annexed drawing shows by way of example two embodiments of the device according to this invention.

Figure 1 shows an embodiment, in which the radially acting balls are arranged at the end and lower part of the spindle and Figures 2 and 3 show on a larger scale a modified form of the device mounted on the spindle end.

Referring to Figure 1 of the drawing, 1 denotes the central part of the spindle, 2 the outer conical part thereof enclosed between the lower piece 3' and upper piece 3, the outer surfaces of which are a continuation of the surfaces of the spindle part 2.

Three openings at 120° from one another are bored in the piece 3 as well as in the piece 3', the upward inclined axes of said holes belong to the same conical surface, the axis of which coincides with the spindle axis. The balls 4 and 4' respectively may be introduced from the outside through said holes.

The balls 4, once on their seats, are prevented from coming out or projecting beyond a maximum extent set by a cap 7 secured to the end of the piece 3 of the spindle and the balls 4' are likewise prevented from coming out or projecting beyond the desired extent by a ring 7' mounted in a suitable seating in the piece 3' under the cone 2 and in continuation thereof,

In the construction shown in Fig. 1 the balls 4 are actuated by a conical surface of a hollow piston 5 provided with a spring 6 in coaxial relation to the spindle, the balls 4' are likewise actuated by a conical surface of the piston 5' operated by the spring 6'. The bobbin to be placed on the spindle, the inner surface c of which is diagrammatically shown in dash and dot lines on the drawing, is centered at its upper and lower part by two rings of radial balls 4 and 4', which are pressed against the surface c by the component of the force transmitted by the light springs 6 and 6' respectively and also by the action of the centrifugal force produced by the weight of the heavy balls 4 during the swift rotation of the spindle.

According to the modified form shown in Figures 2 and 3 in lieu of the hollow piston 5, ball 8 is used, which transmits the pressure of the spring 6 to the balls 4. A similar arrangement is provided at the lower end of the spindle 1.

The form and constructional details of the spindle may obviously be modified from what has been described and illustrated by way of example without departing from the spirit of the invention.

What I claim is:

1. In a spindle for spinning machines and the like, a centering and holding device for a body placed on the spindle, comprising a circular set of balls loosely mounted in radial bores in the spindle, the axes of said openings being inclined and belonging to a single conical surface, the axis of which coincides with the spindle axis, a helical spring arranged in an axial bore in the spindle and a member actuated by said spring and acting on said balls in such manner as to press them simultaneously outwards against said body.

2. In a vertical spindle for spinning machines and the like, a holding and centering device adapted to hold a body to be placed on the spindle, said spindle being provided with radial openings and with an axial bore, the axis of said radial openings being inclined and belonging to a single conical surface, the axis of which coincides with the spindle axis, a circular set of heavy balls loosely mounted in said radial openings, a piston slidably mounted in said axial bore and having a conical surface to press said balls against said body, and a spring coaxially arranged in said bore and acting upon said piston, the centrifugal action of the rotating spindle further tending to force said heavy balls against said body.

3. A spindle for spinning machines and the like, comprising a vertical holding and centering device adapted to hold a body to be placed on said spindle, said spindle being provided with radial openings and with an axial bore, a plurality of heavy balls arranged in a circle and loosely mounted in said axial openings, a single ball displaceably mounted in said axial bore and acting upon said plurality of balls to press them against said body, and a spring arranged in said bore and acting upon said single displaceable ball as to press it between said plurality of balls, the centrifugal action of the rotating spindle further tending to force said plurality of heavy balls against said body.

4. In a spindle for spinning machines and the like, a centering and holding device adapted to hold a body to be placed on said spindle and comprising a circular set of heavy balls loosely mounted in radial openings within said spindle, the axes of said openings being inclined and arranged on a single conical surface, an axial bore in said spindle, a single ball displaceably

mounted in said axial bore and acting upon said circular set of balls to press them outward against said body, and a spring arranged in said bore and acting upon said single displaceable ball as to press it between the balls of said circular set of balls.

5. A spindle for spinning machines and the like comprising a central rod, a conical casing enclosing said rod, plugs at both ends of said casing securing said casing to said rod, said plugs being provided with an axial bore and with radial openings communicating with said bore, the axes of said radial openings being inclined and arranged on the same conical surface, metal balls loosely mounted in said radial openings, stopping means on said plugs for preventing said balls from projecting outside beyond a pre-determined extent, a spring arranged in the axial bore of each of said plugs, and a member actuated by said spring and acting upon said balls to press them simultaneously outward and against said stopping means.

LUIGI MARZOLI.
